(57) CLAIM

We claim the ornamental design for a support for food service equipment, as shown and described.

DESCRIPTION

FIG. 1 is a perspective view of a claimed design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The ornamental design which is claimed is shown in solid lines in the drawings. The broken lines shown are included for the purpose of illustrating the unclaimed portions of the article and form no part of the claim.
